G. S. MEIKLE,
INCANDESCENT CATHODE DEVICE,
APPLICATION FILED AUG. 15, 1916.

1,267,888.

Patented May 28, 1918.

Inventor:
George S. Meikle,
by *Albert S. Davis*
His Attorney.

UNITED STATES PATENT OFFICE.

GEORGE S. MEIKLE, OF SCHENECTADY, NEW YORK, ASSIGNOR TO GENERAL ELECTRIC COMPANY, A CORPORATION OF NEW YORK.

INCANDESCENT-CATHODE DEVICE.

1,267,888.

Specification of Letters Patent. Patented May 28, 1918.

Application filed August 15, 1916. Serial No. 115,109.

To all whom it may concern:

Be it known that I, GEORGE S. MEIKLE, a citizen of the United States, residing at Schenectady, in the county of Schenectady, State of New York, have invented certain new and useful Improvements in Incandescent-Cathode Devices, of which the following is a specification.

The present invention relates to inclosed 10 arc devices and particularly devices having a refractory cathode adapted to operate at incandescence in a gaseous medium.

In Patent 1,182,290 issued to me on May 9, 1916, I have described and claimed a rectifier having an incandescent cathode operating in an atmosphere of neutral gas, as for example argon or nitrogen.

In accordance with my present invention I have discovered that various advantages 20 may be secured by the addition of a quantity of iodin to the neutral gas. For example, the loss of voltage in the arc is lowered and is more constant than in ordinary pure argon. Other advantages will be hereinafter pointed out.

The accompanying drawing shows merely for illustrative purposes one form of arc device in which a gaseous filling embodying my invention may be used.

The device shown in the drawing comprises a cathode 1, consisting of tungsten or other suitable refractory material, and an anode 2 consisting of tungsten, copper, graphite or other suitable conductive material. An anode conductor 3 and cathode conductors 4, 5, are sealed into the envelop 6 in the usual manner.

The device is first evacuated and freed from water vapor and then a desired amount 40 of argon or other gas is introduced, for example, argon to the pressure of several centimeters of mercury and a small quantity of iodin is introduced from a side tube which is then sealed off and removed.

The arc drop of an arc in argon purified before introduction into the device by the usual chemical means is about 16 to 20 volts.

When iodin is present the arc drop is about 11 to 12 volts. The disintegration of the cathode is apparently unaffected by the presence of the iodin. The arc drop is more constant when iodin is present than with pure argon, nitrogen or other neutral gas. The arcing back voltage, or the voltage necessary to start an arc in a reverse direction 55 in the device is greater than with pure argon, or other neutral gas.

The presence of the argon, or other neutral gas enables the arc to be started in the presence of gas without the necessity of 60 first applying heat to vaporize the iodin and the neutral gas enables a desired gaseous pressure to be maintained without requiring the tube to be operated at a high temperature.

What I claim as new and desire to secure by Letters Patent of the United States, is:—

1. The combination of a sealed container, a filling of neutral gas therein, a quantity of iodin, and coöperating electrodes at least 70 one of which is adapted to operate at incandescence.

2. The combination of a sealed container, a filling of argon gas, a quantity of iodin, and coöperating electrodes, the cathode being adapted to operate at incandescence.

3. A rectifier of alternating currents comprising the combination of a sealed container, a filling of argon, a quantity of iodin, a tungsten cathode, means for enabling the 80 cathode to be heated to incandescence, and an anode having a large enough heat dissipating capacity to operate below incandescence.

4. The combination of a sealed container, 85 a filling of neutral gas therein at a pressure of about several centimeters of mercury, a quantity of iodin, a cathode of refractory material operable at incandescence, and a coöperating anode.

In witness whereof, I have hereunto set my hand this 12th day of August, 1916.

GEORGE S. MEIKLE.
